UNITED STATES PATENT OFFICE.

CHESTER F. ALLEN, OF PAW PAW, MICHIGAN, ASSIGNEE TO HIMSELF AND
C. B. BEEBE AND H. TAYLOR.

IMPROVEMENT IN CAR-BUMPER AND DRAW-HEAD SPRINGS.

Specification forming part of Letters Patent No. 35,196, dated May 6, 1862.

To all whom it may concern:

Be it known that I, CHESTER F. ALLEN, of Paw Paw, in the county of Van Buren and State of Michigan, have invented a new and Improved Railroad-Car Bumper and Draw-Head Spring; and I do hereby declare that the following is a full and exact description thereof, reference being had to the accompanying drawings, and to the letters of reference marked thereon, forming a part of this my specification, in which—

Figure 1 is a longitudinal plan of my improved spring; Fig. 2, a longitudinal section of the same; Fig. 3, a plan view of the receiver or cylinder, within which are placed many pieces of india-rubber and of any form; and Fig. 4, a plan view of the piston or follower.

The nature of my invention consists in providing a "receiver" or "cylinder," A, with springs of india-rubber in many pieces and of any form, or other elastic material, b, and a "follower" or "piston," C, to work in said cylinder, as represented in the drawings, and which device, when used as a bumper-spring or a draw-head for locomotives, cars, or other vehicles, may have an ordinary draft-rod passing through the follower and receiver, as represented in the drawings, but which, when used perpendicularly to sustain weight, can be used with or without a rod, as circumstances may require.

To enable others skilled in the art to make and use my invention, I will proceed to describe its construction and operation.

I construct the cylinder or receiver A either of wrought or cast metal and of a capacity sufficient to receive therein the follower or piston C, as shown in the drawings. I construct the follower or piston C of the same metal, and the outside of the follower and the inside of the receiver may be turned and polished or left in their rough state. I then fill the receiver with the elastic material used for the spring. This material consists of many pieces of india-rubber, b, and of any form.

When my improved spring is used in a perpendicular position, I place the receiver upon its pedestal or foundation with the open end upward, and then insert the follower, which should extend into the receiver far enough to keep it in place, at the same time resting upon the pieces of rubber within the receiver. When used horizontally as a bumper or draw-head spring, the ordinary attachment of a draft-rod, D, passing through the receiver and follower, as shown in the drawings, may be applied thereto.

Having thus described my invention, what I claim as new, and desire to secure by Letters Patent of the United States, is—

A car-bumper or draw-head spring constructed substantially in the manner and for the purpose set forth.

CHESTER F. ALLEN.
